SIFTER MECHANISM

William G. Kirchhoff, Cincinnati, Ohio, assignor
to The J. H. Day Company, Cincinnati, Ohio,
a corporation of Ohio

Original application June 27, 1927, Serial No.
201,660, now Patent No. 1,829,707. Divided
and this application April 16, 1929. Serial No.
355,569

8 Claims. (Cl. 209—236)

This application is a divisional application of co-pending application Serial No. 201,660 filed June 27, 1927, which now bears Patent Number 1,829,707. The invention relates to a sifting or 5 dusting apparatus such as may be used with bread making or other types of machines, and has for its object the provision of a sifter mechanism which is adapted for accurate adjustment in order to regulate the quantity of siftable substance discharged thereby.

Another object is to provide a sifter wherein the discharge area of the screen or mesh may be adjusted to suitable dimensions within the range of the screen employed.

15 These and other objects are attained by the means described herein and disclosed in the accompanying drawing in which:

Fig. 1 is a side elevational view of a structure embodying a device of the invention, parts being 20 broken away.

Fig. 2 is a cross sectional view on line 2—2 of Fig. 1.

In the present embodiment of the invention the sifter or duster comprises a body member 8 having side walls 9 which converge downwardly 25 toward a bottom plate 10, which has a longitudinal discharge slot 11. The operative length of discharge slot 11 is controlled by a plurality of slides 12 arranged with parallel abutting sides 30 in side by side relation in a recess 13 in the top face of plate 10. The slides 12 have suitable finger pieces 120 for facilitating withdrawal thereof. A duster screen 14 is secured intermediate the bottom plate 10 and the bottom of the 35 duster body. A suitable agitator shaft 15 extends longitudinally through the duster body and is journaled in a suitable bearing 16 at one end and preferably in an end plate 17 at the opposite end of said body. This shaft is adapted for oscillation by means of any suitable eccentric mechanism, for example, the one described in co-pending application Serial No. 201,660, for imparting a rocking oscillatory movement to a suitable agitator 18 which may carry a plurality of rods 19. 40 The agitator may be rigidly secured to shaft 15 by any suitable means such as set screws 20.

The duster unit or sifter of the invention, together with the eccentric oscillating mechanism E and a suitable driving means such as motor M 50 may be conveniently mounted upon a pair of spaced support members 21, the body of the sifter being provided with perforate base flange 22 resting upon tubular spacer 23, and clamped by bolts 24 extending through the flange, spacer, 55 and into the supports 21. Set screws 25 extend-

ing upwardly through the supports 21 and abutting bottom plate at spaced intervals, serve to retain the bottom plate, screen and the slides 12 in abutment, thereby precluding undesired escape of siftable substance and serving also to eliminate 60 vibration.

The operation of the device is as follows. When it is desired to provide a dusting mechanism for a given machine a complete unit such as is shown in Fig. 1 may be conveniently mounted in 65 position by securing the supports 21 thereto. The extent of movement of the oscillating shaft 15 is adapted to be accurately controlled by adjustment of knob A of the oscillating mechanism E.

It will be understood that the slides 12 may 70 be provided for the entire length of the discharge opening 11 and that they may be drawn outwardly to expose an entire transverse strip of the screen at any given place. With a relatively long discharge opening, the sifter of the present 75 embodiment may be variously arranged by manipulating the slides 12 to provide for a number of aligned spaced discharge openings or they may all be withdrawn to provide one long opening. From this it will be appreciated that the sifter may be readily adapted to effectively co-operate with many types of adjustable machines. It will also be understood that the slides 12, or any of them, may be withdrawn to but partly expose a given portion of the width of the screen 80 so that the quantity of siftable substance discharged during the passage of a moving article to be dusted may be regulated as desired.

What is claimed is:

1. In a sifter structure for uniform distribution of siftable material the combination of a hopper having a continuous discharge slot extending along the body thereof, and means comprising narrow adjustable transversely movable slides disposed adjacent to opposite ends of the discharge slot in close side by side relation for closing end portions only of the slot whereby to provide for predetermined successive reduction in the operative length of the continuous discharge slot without interference with the continuity of the 90 slot intermediate its ends.

2. In a sifter structure the combination of a hopper having a continuous elongated discharge slot therein arranged for uniform distribution of siftable material, an oscillatory agitator for effecting discharge of the contents of the hopper through the slot, means for actuating the agitator, and groups of individual slide members at each end only of the slot, adapted for relative sliding movement and adapted to be moved trans-
